UNITED STATES PATENT OFFICE

GEORGE J. MEYER AND OTTO DREHER, OF MILWAUKEE, WISCONSIN, ASSIGNOR TO
GEO. J. MEYER MANUFACTURING COMPANY, OF MILWAUKEE, WISCONSIN, A COR-
PORATION OF WISCONSIN

CAM OPERATED SWINGING BRUSH FOR BOTTLE WASHING MACHINES

Application filed November 17, 1927. Serial No. 233,926.

The invention relates to bottle washing machines of the type exemplified in Letters Patent No. 1,429,960, issued to George J. Meyer, September 26, 1922, wherein bottles are lifted from an intermittently moving conveyor and when so lifted are carried between rotary brushes for brushing them on the outside.

An object of the invention is to effect the cleaning of bottles and the like by passing them between rotary brushes which are yieldingly mounted for movement apart to adapt themselves to changes in the diameter of the bottles, suitable means being provided, other than the bottles, for determining the varying separation of the brushes while the bottles or other objects to be cleaned are passed between the brushes.

Another object of the invention is to provide cam-operated brush-separating means including a templet member having a contour generally similar to that of the bottles or other objects to be brushed, said templet member being movable simultaneously with the bottles for predetermining the extent of separation of the brushes in accordance with the varying diameter of the bottles.

The invention further consists in the several features hereinafter set forth and more particularly defined by the annexed claims.

In the accompanying drawings, Fig. 1 is a side elevation of a portion of a bottle washing machine showing the cam-operated swinging outside brushes of this invention;

Fig. 2 is a transverse elevation of the brushing mechanism, parts being broken away and parts being shown in section; and

Fig. 3 is a sectional elevation through the outside brushing mechanism, showing the bottle lifting mechanism holding one bottle between the brushes and another with its bottom against one of the brushes.

In these drawings, 10 indicates the frame of a bottle washing machine which may be such as that shown in the Meyer patent above noted, and 11 represents the rows of bottle holders of the intermittently moving bottle conveyor thereof by the intermittent movements of which the rows of bottles are successively brought into position to be oper-

ated upon by exterior washing mechanism, constituting this invention and to be described in detail, and by interior washing and rinsing mechanism represented by a portion 12 thereof. The bottles 13 travel 55 through the machine from left to right as viewed in Fig. 1 and reach the part of the machine shown to receive an external cleaning preliminary to their internal cleaning.

As in the patent referred to above, there is 60 provided a vertically reciprocating bottle-lifting mechanism consisting of rotating upright spindles 14 to enter the mouths of bottles in one row of bottle holders and lift these bottles between a pair of oppositely rotating 65 brushes 15 while turning them and reciprocating them between the brushes to expose all parts of the outer surface of the bottles to the cleaning action of the brushes, while spray pipes 16 supply water for the cleaning operation. 70

A brush-supporting frame consisting of arms 17 mounted on a shaft 18 is pivotally supported in the main frame 10 by said shaft fitting in bearings 19, and is counterbalanced 75 by weights 20 mounted on the rearwardly-directed extension at one end of said shaft. On the other end of the shaft is journaled a driving pulley 21 for driving the brushes. Upon the horizontally extending arms 17 is a housing 22 covering the brushes and confining the water spray and this housing is adjustable on the arms 17, to position the brushes with respect to the bottle lifting mechanism, by clamping means 23 at the rear end of the housing, and by set screws 24 in brackets 25 of the housing, through which the arms 17 pass. 80

Jack screws 26 threaded through said brackets and passing through slots of the arms, bear on stationary supports 27 to adjustably 85 determine the normal elevation of the brushes, though the brushes may be readily lifted because of their supporting frame being pivotally mounted and counterbalanced.

The two spray pipes 16 are mounted to oscillate in bearings at opposite ends of the housing, the pipes being provided with hose connections 28, through which water is supplied for the forcible sprays directed against the bottles. Fixed on these spray pipes at 95 100

both ends of the housing are brush hangers 29 in the form of bell-crank levers having the brushes 15 journalled in their longer depending arms and having intermeshing gear segments 30 on their shorter arms, so that the 5 brushes move in unison toward or away from the vertical central plane between them in which the bottle-lifting mechanism operates.

Loosely mounted on the ends of the spray 10 pipes 16 are brush-driving sleeves 31 each having a chain and sprocket connection 32 with the brush 15 therebeneath. The sleeves are meshed together with intermeshing gears 33 thereon so as to turn the brushes at the same 15 speed but in opposite directions, as indicated by arrows, and receive their drive from the drive pulley by one of them having a chain and sprocket connection 34 therewith.

It will be noted that although the weight 20 of the brushes tends to cause them to swing toward each other, this tendency is opposed by the direction of the drive thereon, for the influence of the drive is to cause the brushes to spread apart. It is the purpose of the present invention, however, to positively effect the 25 variable separation of these brushes in accordance with the varying diameter of the bottles inserted between the brushes, to thereby avoid undue deflection of the brush bristles 30 with the result that such bristles are more effective in their action and the life of the brushes is materially increased. In the present instance, this positive but varying separation of the brushes is accomplished by a reciprocatory cam templet 45 corresponding generally to the contour of the bottles and engageable at opposite side edges with rollers 46 carried on laterally-extending projections 47 formed at the lower depending arms of the 40 brush-carrying bell-crank levers 29. The templet 45 is carried on an upstanding rod 48 which is detachably secured at its lower end within a socket 49 in an end extension of the miter-gear cross-head 40 on which the 45 rotating upright spindles 14 are supported, the cross-head 40 being slidably mounted for vertical movement on vertical guide bars 50. The spindle-carrying cross-head 40 is raised periodically in any suitable manner, such as 50 by means of an oscillatory rocker arm 51, having its free end connected to the cross-head by a link 52, the rocker arm being mounted on a shaft 53 disposed on a fixed axis.

In order that the brushes may be quickly 55 removed and replaced, they are journalled in removable bearing bushings 35 suitably mounted in the bell-crank levers against relative rotation. The axial removal of the bushings exposes slots 39 in the ends of the bell- 60 crank levers which are of sufficient width to permit the brush trunnions to pass therethrough, thereby avoiding an extensive dismantling operation.

It is found desirable to mount the brushes 65 15 above the level of travel of the bottoms

of the bottles on the conveyor so that the right-hand brush, as viewed in Figs. 1 and 3, will not spatter dirt onto the bottles that have received an outside cleaning. Instead, it is desirable to slightly lift the bottles of 70 the row following the row being lifted between the brushes to have their bottom surfaces brushed by the left-hand brush of Fig. 1, for such dirt as may be spattered by that brush will not fall upon bottles that have 75 been cleaned.

To accomplish the lifting of bottles for the bottom cleaning, the miter-gear cross-head 40 which is raised periodically for lifting a row of bottles between the brushes, as 80 hereinbefore described, has mounted thereon clamp members 41 carrying upstanding pins 42 in position to enter the bottles of the said row, and these pins are of such length that they engage the bottoms of the bottles and 85 lift them so that they bear against the brush, as shown in Fig. 3. Inasmuch as the bottles are lifted by means engaging their bottoms instead of their necks, no adjustment is required when shorter bottles are used. 90

The improvements constituting the present invention make for a thorough cleaning of the outside of the bottles with a minimum of wear and consumption of power, since the brush bristles while engaging the bottles 95 are deflected no more than is necessary. When bottles of different diameter or contour are to be cleaned, it is only necessary to remove the templet rod from its socket in the cross-head and substitute another one 100 having a cam contour to correspond with the bottles.

The brushing means of this invention can also be used for the cleaning of cans, jars, and other like receptacles. 105

What we claim as new and desire to secure by Letters Patent is:

1. In a bottle washing machine having a bottle conveyor, the combination of a reciprocable bottle-lifter for engaging a bottle 110 and lifting it from the conveyor, a pair of brushes between which the bottle is moved by the bottle-lifter, means for supporting the brushes, and means coupled with the bottle-lifter for separating the brushes a variable distance to correspond with the varying diameter of the bottle as it is passed between the brushes. 115

2. In a bottle washing machine having a bottle conveyor, the combination of bottle-lifting means for engaging and lifting a bottle from the conveyor, rotatable brushes between which the bottle is moved by the bottle-lifting means, displaceable supports for the brushes permitting them to move 120 apart, and cam means acting on said displaceable supports for separating the brushes a variable distance to correspond with the varying diameter of the bottle as it is passed between the brushes. 125

3. In a bottle washing machine, the combination of a pair of brushes, means for moving a bottle between the brushes, yielding means supporting the brushes for permitting their variable separation during the passage of the bottle therebetween, and means coupled with the bottle-moving means acting on said brush-supporting means for separating the brushes a variable distance to correspond with the varying diameter of the bottle as it is passed between the brushes. 10
4. In a bottle washing machine, the combination of a pair of brushes, means for moving a bottle between the brushes, yielding means supporting the brushes for permitting their variable separation during the passage of the bottle therebetween, and a reciprocable cam movable simultaneously with the bottle-moving means and acting upon said yielding brush-supporting means for urging said brushes apart a variable distance to correspond with the varying diameter of the bottle as it is passed between the brushes. 15
5. In a bottle washing machine having a bottle conveyor, the combination of means for lifting a bottle from the conveyor, rotatable brushes between which the bottle is passed by the bottle-lifting means, levers by means of which the brushes are supported, and a cam-forming templet member reciprocated simultaneously with said bottle-lifting means and acting upon said brush-supporting levers for urging said brushes apart a variable distance to correspond with the varying diameter of the bottle as it is passed between the brushes. 20
6. In a bottle washing machine having a bottle conveyor, the combination of bottle lifting means for engaging and lifting a bottle from the conveyor, rotatable brushes between which the bottle is moved by the bottle-lifting means, swinging supports for the brushes permitting their movement apart, and a cam member mounted for reciprocation with said bottle-lifting means and having cam surfaces at opposite sides engageable with said swinging brush supports for urging said brushes apart a variable distance to correspond with the varying diameter of the bottle as it is passed between the brushes. 25
7. In a bottle washing machine, the combination of a pair of brushes adapted to receive a relatively movable bottle therebetween, means for supporting the brushes for movement apart, means for effecting the relative movement of said bottle between said brushes, and means operatively connected with said last-named means for separating the brushes a variable distance to correspond with the varying diameter of the bottle as it is passed between the brushes. 30
8. In a bottle washing machine having a bottle conveyor, the combination of bottle-lifting means for engaging and lifting a bottle from the conveyor, brushes between
- which the bottle is moved by the bottle-lifting means, displaceable supports for the brushes permitting them to move apart, and cam means acting on said displaceable supports for separating the brushes a variable distance to correspond with the varying diameter of the bottle as it is passed between the brushes. 35
9. In a bottle washing machine having a bottle conveyor, the combination of means for lifting a bottle from the conveyor, brushes between which the bottle is passed by the bottle-lifting means, levers by means of which the brushes are supported, and a cam-forming templet member reciprocated simultaneously with said bottle-lifting means and acting upon said brush-supporting levers for urging said brushes apart a variable distance to correspond with the varying diameter of the bottle as it is passed between the brushes. 40
10. In a bottle washing machine having a bottle conveyor, the combination of bottle-lifting means for engaging and lifting a bottle from the conveyor, brushes between which the bottle is moved by the bottle-lifting means, swinging supports for the brushes permitting their movement apart, and a cam member mounted for reciprocation with said bottle-lifting means and having cam surfaces at opposite sides engageable with said swinging brush supports for urging said brushes apart a variable distance to correspond with the varying diameter of the bottle as it is passed between the brushes. 45
11. In a bottle washing machine, a pair of opposed brushes, means for moving a bottle axially between said brushes, the bristles of both said brushes being adapted to contact said bottle, and means for moving said brushes toward and from each other a variable distance corresponding substantially to the varying diameter of the bottle as it is moved axially with respect to said brushes, said means including a cam movable with the bottle moving means and a cam follower connected with each of said brushes. 50
